1,960,800

MANUFACTURE OF LINED BOXES

John S. Stokes, Huntingdon Valley, Pa., assignor
to Stokes and Smith Company, Philadelphia,
Pa., a corporation of Pennsylvania

Application June 28, 1930, Serial No. 464,593
Renewed March 5, 1932

18 Claims. (Cl. 93—43)

My invention relates to the lining of boxes, cartons, containers or the like, hereinafter generically termed "boxes".

The better grade of wrapped box is formed of cardboard, or other box material, which is lined, or covered on the surface to form the interior of the box with paper, or like sheet material. Heretofore, box manufacturers have found it necessary to keep in stock various sizes of lined sheets which are made by cutting cardboard sheets to size, cutting lining paper to size, and delivering the cut sheets to a lining machine. To fill an order for boxes of a specified size, it was necessary to procure the proper number of lined sheets from storage, trim them to proper size, transport the trimmed blanks to scoring machines, then to corner-cutting machines, thereafter to staying machines, and eventually to wrapping machines. In addition to the waste occasioned by trimming, many partially formed boxes or blanks are rendered unfit for use by injury received during the many transportation steps and operations involved. The method is expensive also because of the many machines and operators necessary.

In accordance with my invention, as a strip of box material of exact width to form a box component, is removed, as from a roll, and more specifically, while it is being fed toward a fabricating station, as to the form-block structure of a wrapping machine, covering paper of the same or proper width removed from a roll of proper width is adhesively applied thereto; more particularly, cutting of the composite strip into pieces of proper length produces box components which may be delivered directly to the fabricating station where, with complementary box components similarly prepared they are arranged in box-forming position and permanently attached, as by application of wrappers, to form lined boxes. By this method, the waste of material is greatly reduced; there is great saving of space, and the number of steps necessary to form the boxes is materially lessened.

Further in accordance with my invention, reinforcing strips are applied to a strip of box material before it is cut, and preferably to the surface to which the lining paper is subsequently applied.

My invention further resides in the methods and features hereinafter described and claimed.

For an understanding of my invention and illustration of some of the forms of boxes produced, reference is to be had to the accompanying drawings in which in perspective:

Fig. 1 illustrates rolls of box, tabbing, and lining material with associated scoring or creasing, adhesive applying and cutting mechanisms.

Fig. 2 discloses a main box blank bent along its scoring or creasing. 6000

Fig. 3 illustrates a tabbed coated wrapper.

Fig. 4 discloses a blank of Fig. 2 superimposed upon the wrapper of Fig. 3.

Fig. 5 shows rolls of box and lining material, associated knives, and wrapping machine form 6500 block structure.

Figs. 6 to 10 inclusive, illustrate the successive steps of forming and wrapping a lined composite box.

Fig. 11 illustrates modified forms of box components. 7000

Referring to Fig. 1 the roll R of suitable box material, as cardboard, or the like, is continuously or intermittently rotated, and as the strip is unrolled, engagement is effected with tapes t 7500 of tabbing material, as paper, withdrawn from the rolls r. Fresh adhesive is applied to the tabbed strips, or adhesive thereon is moistened, by the rollers G as the strips pass thereover prior to engagement with the strip of box material. 8000 Lining material, as paper, withdrawn from the roll L, is applied to the surface of the strip of box material destined to form the interior of the box, which in the example shown, is the same surface to which the tabbing strips have been 8500 previously applied, the lining strip covering the tabbing. The tabbed, lined strip is cut as by the knives K1 to form box components C, each of which, as shown to the right of Fig. 1, comprises a portion A adapted to form the bottom of a box and portions or sections S adapted to form opposite walls, as said walls of a box. 9000

Preferably before cutting of a blank from the strip of box material, the strip is scored or creased, as by knives or rolls K to facilitate bending of the blanks, and when the tabbing is applied to the undersurface of the strip, the scoring or creasing is necessarily effected prior to the application of tabs.

As shown most clearly in Fig. 2, in which part 100 of the lining material is broken away, the tab strip t overlies the scoring or creasing to reinforce the inside corners of the box formed by the panels S and A.

Preferably each component C, as formed, is fed 1000 toward a wrapping station. For example, the prepared component C, Fig. 2 is aligned with a wrapper W, Fig. 3, as shown in Fig. 4, and the assembly thus formed is delivered to a wrapping station, as to the form block structure of a wrapping ma- 110

chine. The wrapper W, which is freshly coated with adhesive, is preferably tabbed, the tabbing being so disposed that when the panel A of the main component C is registered with the corresponding panel a of the wrapper, the tabs t1 thereon project in part beyond the edges of the main component as shown in Fig. 4.

During preparation of the main component, minor components adapted for example, to form 10 end walls of the box are being prepared in generally the same manner. Preferably adjacent the form block structure F, there are disposed rolls R1, of box material, on opposite sides of the form block. Sheet lining material fed from the rolls 15 L1, is applied to the surfaces of the box material strips destined to form the inside of the box, the rolls G2 supplying adhesive to, or moistening adhesive upon, the side of the lining strips contacting with the box material. The composite 20 strips are cut as by the knives K2 to form end wall components E, E.

The feeding of the rolls R1, and operation of knives K2, is preferably timed with respect to the feeding of roll R and the cutting of components C therefrom, so that groups of components, each group comprising a main component C and a pair of end components E are delivered in succession to the wrapping station.

Referring to Fig. 5, the lined end wall components E, E are swung into position registering 30 with opposite ends of the form block structure F, the lined surfaces of the components being in contact with the blank. They are held in position by suitable means forming no part of the present 35 invention. The assembly of Fig. 4 comprising the main component C and wrapper W adhering thereto, is brought for example, into the path of movement of the form block structure F, so that upon descent of the form block, the end components E are brought into box-forming position 40 with the main component C.

During the wrapping operation, side panels s of the wrapper are brought into adhesive engagement with the unlined surfaces of side panels S 45 of component C, Fig. 7, the corner lap portions f of the side panels s subsequently folded into adhesive engagement with the end wall components E, E, Fig. 8, the tab structure t1 overlying the vertical corners of the box formed by the components 50 E and C. Subsequently the end panels e are folded upwardly into adhesive engagement with the end wall components E, the central portion of the tab structure t1 overlying the lower end 55 corners of the box formed by the end wall components E and the bottom A of the box, Fig. 9.

Thereafter, the portions m of the wrapper, projecting beyond the top of the box are folded over the top edge and downwardly into engagement with the interior of the box, or more specifically, 60 the lined surface of the components E and C.

As shown in Fig. 11, the lining material need not completely cover the surface of the components C and E, forming the interior of the box, but may terminate short of the edges of the 65 components forming the top edge of the box, leaving an exposed or uncovered portion M which however, is covered by the marginal turn-in portions m of the wrapper during the wrapping operation, these turn-in portions completing the 70 lining of the box material. The advantages are two-fold, as the width of the rolls L and R1 of lining material may be correspondingly less, and the coarser surface of the box material is superior to the relatively smooth surface of the lining ma-

terial for receiving the adhesive upon the marginal turn-in portions m of the wrapper.

While one group of components is being wrapped, one or more other groups are in course of preparation, so that the method is continuous with no storage of components which would involve transportation and repeated handling.

While all of the steps may be performed manually, at least many of them may be effected mechanically. For example, the feeding of the box component and wrapper assembly of Fig. 4, to the form block structure F, the cutting of the end wall box components from continuous strip material and feeding of end components so cut to the form block structure, and the uniting of the components in box-forming position during a wrapping operation, can be effected by a box machine similar, for example, to that of co-pending Rider application, Serial No. 460,859, filed June 13, 1930.

For brevity in the appended claims, the term "scoring" shall be deemed as generic to either "scoring" or "creasing".

What I claim is:

1. The method of making a lined box which 100 comprises adhesively applying strips of sheet lining material to strips of box material, severing the composite strips to form lined box components, assembling the box components in box-forming position with the lined surfaces of said components forming the interior of the box, and adhesively applying a wrapper to the exterior of the lined box thus formed to attach said components.

2. The method of making a lined box which 110 comprises adhesively applying strips of sheet lining material to strips of box material, scoring one of said strips to define box wall sections, severing the composite strips to form lined box components, bending the scored component along 115 the scoring and bringing the other components into box-forming relation thereto with the lined surfaces of said components forming the box interior, and adhesively applying a wrapper to the unlined surfaces of the components simultaneously to attach them in said relation and to wrap 120 the box formed thereby.

3. The method of making a lined box which 125 comprises adhesively applying tab structure to a strip of box material, adhesively applying sheet lining material to the tabbed surface of said strip, severing the tabbed, lined strip to form a box component, adhesively applying other strip sheet lining material to other box strip material, severing the composite strip material to form complementary box structure, assembling the tabbed lined component and the lined complementary box structure in position to form a box with a lined interior, and adhesively applying a wrapper 130 to the exterior of the box thus formed.

4. The method of making lined boxes which 135 comprises feeding strips of box material from rolls thereof, adhesively applying thereto sheet lining material fed from rolls thereof, severing the composite strips to form groups of box components assembling the groups of components in succession in box-forming relation with the lined surfaces of each group of components forming the interior of a box, and in succession adhesively applying wrappers to the groups of components in said box-forming position.

5. The method of making lined boxes which 140 comprises feeding strips of box material from rolls thereof toward a wrapping station, adhesively applying thereto sheet lining material fed 145

- from rolls thereof, severing the composite strips to form groups of box components, feeding the groups in succession to the wrapping station, and at said station and in succession adhesively applying a wrapper to each group of components in box-forming position with the lined surfaces of the components facing the interior of a box. 6. The method of making lined boxes which comprises feeding a strip of box material from a roll thereof, scoring the strip to define wall sections of a box, adhesively applying to the strip sheet lining material fed from a roll thereof, severing the strip to form main box components each adapted to form a box bottom and opposite side walls, feeding strips of box material from rolls thereof toward a wrapping station, adhesively applying to the strips sheet lining material removed from rolls thereof, severing the strips to form minor box components each adapted to form a box end wall, delivering to the wrapping station in succession groups of components each comprising a scored main component and a pair of minor components, in succession assembling the components of the group in box-forming position with the lined surfaces of said components forming the box interior, and at said station and in succession, adhesively applying a wrapper to attach the components in said box-forming position and to wrap the box formed thereby. 7. The method of making a lined box which comprises lining individual box components, assembling the components in box-forming position with the lined surfaces forming the box interior, and by adhesive application of a wrapper, concurrently attaching said components in box-forming position and wrapping the box formed thereby. 8. The method of making a lined box which comprises lining a rectangular piece of box material adapted to form the bottom and side walls of a box, lining rectangular pieces of box material adapted to form end walls of a box, assembling the lined pieces in position to form a box with the lined surfaces forming the box interior, and by adhesively applying a wrapper to the exterior of the box thus formed concurrently attaching the lined pieces in box-forming position and wrapping the box formed thereby. 9. The method of making a lined box which comprises lining a rectangular box component, scoring the component to define bottom and side wall sections, adhesively applying tab structure to said component to reinforce the scored portions thereof, lining rectangular box components adapted to form box end walls, assembling the lined components in position to form a box with the lined surfaces thereof comprising the box interior, and adhesively applying a tabbed wrapper to the box exterior, to attach said components, the tabbing thereof overlying the vertical and lower end corners of the box. 10. The method of making a lined box which comprises scoring a strip of box material on one side thereof, applying tab structure to the other side of said strip opposite the scoring, adhesively applying strip lining material to said strip to overlie the tabbing thereon, severing the strip to form a main box component, adapted to form the bottom and side walls of a box, the tab structure united thereto reinforcing the lower side corners of the box, adhesively applying strip lining material to other strips of box material, severing the lined strips to form components adapted to form end walls of a box, assembling the main component bent along said scoring and the end wall components in box-forming position with the lined surfaces forming the box interior, and adhesively applying a tabbed wrapper to the box exterior to attach said components thereof, the tabbing thereon overlying the vertical and lower end corners of the box. 11. The method of making a lined box which comprises lining individual box components, assembling the components in box-forming position with the lined surfaces forming the box interior, adhesively applying a wrapper to the box exterior to attach said components, and folding portions of the wrapper over the top edges of the box and downwardly into adhesive engagement with the lined surface of the components. 12. The method of making a lined box which comprises adhesively applying lining material to individual box components leaving uncovered a portion of each, assembling the components in box-forming position with the lined surfaces forming the box interior and the uncovered portion of said surfaces at the top of the box, adhesively applying a wrapper to the box exterior to attach said components, and folding portions of the wrapper over the top edges of the box and downwardly into engagement with the uncovered portion of said components to complete the lining of the box. 13. The method of making a lined box which comprises adhesively applying strips of sheet lining material to strips of box material, severing the composite strips to form lined box components, assembling the box components in box-forming position with the lined surfaces of said components forming the interior of the box, and adhesively applying sheet material to the exterior of the lined box thus formed to attach said components. 14. The method of making a lined box which comprises feeding strips of box material from rolls thereof, adhesively applying thereto sheet lining material fed from rolls thereof, severing the composite strips to form groups of components, assembling the groups of components in succession and before setting of any of said adhesive in box forming relation with the lined surfaces of each group of components forming the box interior, and without substantial delay adhesively applying sheet material to unite the components of each group in box-forming position. 15. The method of making lined boxes which comprises adhesively applying a strip of sheet lining material to a strip of box material, severing the composite strip to form lined components each adapted to form the bottom and opposite sides of a box, adhesively applying a strip of sheet lining material to a strip of box material, and severing the second composite strip to form lined box end components. 16. The method of making lined boxes which comprises adhesively applying a strip of sheet lining material to one face of a strip of box material, scoring the strip of box material, severing the scored and lined strip to form box elements, and adhesively applying individual wrappers to cover the unlined face of each of said box elements. 17. The method of making lined boxes which comprises adhesively applying tab material to a strip of box material, adhesively applying sheet lining material to one face of said strip of box material, scoring the strip of box material, severing the tabbed, scored and lined strip to form box

elements, and adhesively applying individual wrappers to cover the unlined face of each of said box elements.

18. The method of making lined boxes which 5 comprises adhesively applying tab material to a strip of box material, adhesively applying sheet lining material to one face of said strip of box material, scoring the strip of box material, sev-

ering the tabbed, scored and lined strip to form box elements, and adhesively applying individual tabbed wrappers to cover the unlined face of each of said box elements, the tabbing on the wrappers supplementing the tab material previously applied to the box elements while in strip form.
